UNITED STATES PATENT OFFICE.

IDA C. ROSSOM, OF DULUTH, MINNESOTA.

DISINFECTING DEVICE.

1,096,461.

Specification of Letters Patent.

Patented May 12, 1914.

Application filed May 14, 1913. Serial No. 767,558.

To all whom it may concern:

Be it known that Ida C. Rossom, a citizen of the United States, residing at Duluth, in the county of St. Louis and State of Minnesota, have invented certain new and useful Improvements in Disinfecting Devices, of which the following is a specification.

My invention relates to disinfecting devices for use particularly in connection with lids of refuse receptacles.

I aim to provide a structure which may be readily applied to the lid in a manner that a chamber is formed between the inner surface of the lid structure and my attachment, the main portion of the attachment being constructed of reticulate material to afford sifting of a powdered disinfectant therethrough during the ordinary use of the receptacle.

20 A further object is to make the attaching means for this partition of a hinged construction whereby it may be swung to open position, as in a case of refilling, then may be swung to its operative position and securely clasped.

Further objects of my invention will be apparent from a detailed description of the accompanying drawings, in which similar characters of reference designate corresponding parts, and in which:

Figure 1 is a bottom plan view of the partition structure used in the present device, Fig. 2 is a central vertical section of a portion of a refuse can showing my invention applied thereto, Fig. 3 is a detail view in perspective showing the clasp connection used by me, and, Fig. 4 is a detail view in perspective of the hinge connection used in applying my invention to a receptacle.

40 In the drawings, the main receptacle 1 is shown as being provided with a top cover 2, this cover having a depending peripheral flange 3, whose lower edge terminates in a curled portion 4. My partitioning device is

45 designed to be applied to the inner side of the lid 2 and is shown in this position in Fig. 2. This partition is formed of a circular wire 5 over which is secured a piece of wire mesh or other suitable reticulate material 6. By securely mounting this partition in the position shown in Fig. 2, it will be apparent that any disinfecting powder placed in the chamber formed beneath the under surface of the lid 2, will be gradually sifted through the wire mesh during re-

moval and replacement of the lid from its operative position. However, to slightly reduce the area through which this powder may be sifted and to provide a reinforcing structure, I have securely mounted the 60 spider 7 upon the ring 5 and have attached a handle 8 thereto to permit of its being readily handled. In order that this partition may be readily swung to an open position, I have provided one of the legs of the 65 spider 7 with a curled projecting lip 9 adapted to coact with complementary curled lips 10 of a depending element 11. A pin 10^a is passed through the curled portions 9 and 10 to form a pivotal connection between the element 11 and the spider 7. A similar pivotal connection between the element 11 and the hinge member 12 is also provided, as shown at 13. It will be noted that the hinge element 12 is of substantially 70 right angular formation and has its upwardly extending leg provided with a curled portion 14 constructed to engage the curled edge 4 of the lid 2. By attaching the hinge element 12 to this lid 2 in any preferred manner, the partition itself may be 75 swung outwardly about the pivotal connections 10^a and 13.

At a point directly opposite the hinge connection just described, I have pivotally 80 attached a clasp element 15 as more clearly shown at 16. The lower end 17 of this clasp element is also curled and is designed to resiliently engage the curled portion 4 of the lid at a point opposite the hinge connection. 85 It will, therefore, be apparent that if it is desired to remove the partition from its position shown in Fig. 2, the clasp element 15 is unlatched and swung slightly inward about its pivotal connection 16. An outward 90 pull will cause a swinging of the partition about its hinge connections 10^a and 13 as has been previously related.

What I claim, is:

1. The combination with the lid of a refuse receptacle, said lid being formed with a depending flange terminating in a rolled edge, of a reticulate partition across the inside of said lid to form a chamber, an element pivotally attached to said partition 105 and extending downwardly to the edge of said flange, a hinge member pivoted to the bottom of said element and engaging the curled edge of said flange, and a clasp member pivoted to said partition at a point op- 110

posite said hinge member and having its lower edge curled to resiliently engage the curled edge of the depending flange.

2. The combination with the lid of a refuse receptacle, said lid being formed with a depending flange terminating in a rolled edge, of a disinfecting attachment comprising a reticulate partition fitting in said lid to form a chamber, an element pivotally attached to said partition and extending downwardly to the edge of said flange, a hinge member pivoted to the bottom of said element and engaging the curled edge of

said flange, a clasp member pivoted to said partition at a point opposite said hinge member and having its lower edge curled to resiliently engage the curled edge of the depending flange, and a powdered disinfectant in said chamber adapted to sift through said partition on movement of said lid. 15 20

In testimony whereof I affix my signature in presence of two witnesses.

IDA C. ROSSOM.
